STEAM RADIATOR

Bo Folke Randel, San Diego, Calif.

Application January 27, 1936, Serial No. 60,967

4 Claims. (Cl. 236—41)

(Granted under the act of March 3, 1883, as
amended April 30, 1928; 370 O. G. 757)

This invention relates to heat radiating systems and it has a particular relation to devices for automatically controlling the temperature thereof.

In a common steam radiator with a conventional trap, or without trap if desired, in which the condensate return is closed, the steam will continue to condense, gradually filling the radiator with water. As the radiator is filled with water, the heat radiating surface in contact with the heat medium, steam, is reduced until the radiator is completely filled with liquid. Thus, by closing or throttling the condensate outlet, the heat output of the radiator may be reduced finally to zero. This action of course, is not so rapid as if the steam inlet valve was closed, but often such rapid action is not desired. If more rapid action is desired, the closing of the condensate discharge pipe may be adjusted so as to anticipate a certain effect at a certain time.

The principal object of the invention is the provision of a device of the character described for automatically controlling the discharge of the condensate from a steam radiator and thus indirectly controlling the supply of steam thereto.

Another object of the invention is the provision of a simple and efficient temperature actuated valve mechanism for controlling the flow of a heating medium in accordance with the temperature of the surrounding atmosphere or environment.

With these and other objects in view, as well as other advantages that may be incident to the use of the improvements, the invention consists in the parts and combinations thereof herein-after set forth and claimed, and with the understanding that the several necessary elements constituting the same may be varied in proportion and arrangement without departing from the nature and scope of the invention, as defined in the appended claims.

In order to make the invention more clearly understood, there are shown in the accompanying drawing, means for carrying the invention into practical use, without limiting the improvements in their useful application to the particular construction, which, for the purpose of explanation, have been made the subject of illustration.

In the accompanying drawing:

Fig. 1 is a vertical sectional view of a temperature actuated valve constructed in accordance with the invention;

Fig. 2 is a similar view of another form of the invention;

Fig. 3 is a similar view of still another form of the invention; and

Fig. 4 is a diagrammatic view on a smaller scale of a heat radiator equipped with the improved temperature actuated valve for controlling the discharge of condensate therefrom.

Referring to the drawing, and particularly to Fig. 4 thereof, a temperature actuated valve embodying the invention and indicated generally at 10 is shown as being connected with the steam and condensate discharge pipe 11 of a conventional steam radiator 12 of the sectional type and supplied with steam from a pipe 13.

As shown in Fig. 1, the valve 10 preferably comprises a casting 14 having a valve chamber 15 formed therein communicating through a nipple 16 with the condensate discharge pipe 11 of the radiator 10 and through a nipple 17 with an escape pipe or drain 18. The nipple 17 is provided with a seat 19 for engagement by a valve 20 fixed to the lower end of a valve stem 21. The upper end of the valve stem 21 is fixed to the lower surface of an expandable and contractible bulb 22 which is filled with a suitable volatile liquid and which is responsive to the temperature of the heating medium. A rod 23 is fixed to the upper surface of the bulb 22 and extends vertically through a bellows 24 to which it is fixed and sealed. If desired, a packing gland may be substituted for the bellows 24. The bellows 24 seals the upper portion of the chamber 15 and is clamped between a peripheral flange 25 formed on the casting 14 and a flange 26 formed on the lower end of a cage 27. This construction permits of the vertical movement of the valve 20 and at the same time preventing leakage.

The upper end of the rod 23 is fixed to the lower end of a receptacle 28 adapted to contain a volatile liquid 29 and provided with a plurality of cooling fins 30. This receptacle communicates at its upper end with a bellows 31 to which it is fixed and sealed as against leakage. The receptacle 28 and bellows 31 are both located within the cage 27 where they are in contact with the atmosphere and are responsive to room temperature. The range of movement of the bellows 31 and the parts connected therewith under the influence of fluctuations in room temperature, is controlled by an adjusting screw 32 which is rotatably mounted in the upper end of the cage 27 for screw threaded engagement with a block 33 fixed to the upper face of the bellows 31 and which is provided with an operating knob 34 at its upper end.

At low room temperatures the bellows 31 will be in a contracted condition due to the shrinkage of the volatile liquid 29, thus holding the valve 20

unseated through the medium of the interconnecting parts. This will permit of an unobstructed circulation of steam through the radiator 11. As the temperature of the room raises, 5 the bellows 31 will gradually expand until the valve 20 engages its seat 19 and cuts off the circulation of the steam which condenses in the radiator and collects in the lower portion thereof and in the chamber 15. This condensate will 10 gradually accumulate in the radiator with a resulting diminution in the space occupied by the live steam and the heat radiated by the radiator. Under normal conditions the bulb 22 will permit the escape of the condensate but will expand and 15 close the valve 20 when live steam enters the chamber 15. The action of this bulb is, however, controlled by the adjustment of the screw 32 and the temperature of the room.

In Fig. 2 there is illustrated a slightly different 20 embodiment of the invention wherein the reservoir 28 and bellows 31 are located at a place remote to the valve chamber 15 and the radiator. In this construction the reservoir 28 communicates with a bellows 35 through a pipe 36. The bellows 35 has its upper surface fixed to the upper end of the cage 27 and its lower face secured to the upper end of the rod 23. Obviously, 25 any expansion or contraction of the liquid in the receptacle 28 will be transmitted through the liquid in the pipe 36 and bellows 35 so as to cause a corresponding movement of this bellows and the valve 20 connected therewith. In other respects the operation of this mechanism is similar 30 to that described in connection with Fig. 1.

35 In Fig. 3 there is illustrated a still further modification of the invention in which the trap bulb 22 is dispensed with. With this change, the structure is the same as that shown in Fig. 3. It will be understood that the bulb 22 may also 40 be omitted in the structure shown in Fig. 1 if so desired.

Other modifications and changes in the proportions and arrangement of the parts may be made by those skilled in the art without departing 45 from the nature and scope of the invention as defined in the appended claims.

The invention described herein may be manufactured and used by or for the Government of the United States of America for governmental purposes without the payment of any royalties 50 thereon or therefor.

I claim:

1. In combination with a steam radiator having inlet and outlet pipes, a valve mechanism located 55 in said outlet pipe and responsive to the tempera-

ture of both the atmosphere and the steam in said radiator for controlling the discharge of condensate from the radiator, thus to vary the internal area of the radiator exposed to the heating effect of the steam.

2. In combination with a steam radiator having inlet and outlet pipes, a valve for controlling the discharge of condensate from the radiator and a bellows containing a fluid expandible and contractible with changes in the temperature of both 10 the atmosphere and that of the steam in said radiator for controlling said valve, thus to vary the internal area of the radiator exposed to the heating effect of the steam.

3. In combination with a steam radiator having 15 inlet and outlet pipes, a valve mechanism located in said outlet pipe and comprising a chamber, a valve member in said chamber for controlling the escape of condensate from said radiator, means responsive to the temperature of the condensate 20 in said chamber and radiator for actuating said valve member, a movable receptacle connected to said valve member and located exterior to said chamber and in contact with the outer atmosphere for containing a volatile fluid, and an expandible chamber connected to and communicating with said receptacle and adapted to move the same to also actuate said valve member with fluctuations in the volume of the fluid in said receptacle caused by changes in the temperature 25 of said outer atmosphere, thus to control the volume of condensate in the radiator and the volume of heating medium admitted thereto.

4. In combination with a steam radiator having 30 inlet and outlet pipes, a valve mechanism located 35 in said outlet pipe and comprising a chamber, a valve member in said chamber for controlling the escape of condensate from said radiator, an expandible bulb disposed within said chamber and responsive to the temperature of the condensate 40 therein and in said radiator for actuating said valve member, a movable receptacle connected to said valve member and located exterior to said chamber and in contact with the outer atmosphere for containing a volatile fluid, and a bellows connected to and communicating with said receptacle and adapted to move the same to also 45 actuate said valve member with fluctuations in the volume of the fluid in said receptacle caused by changes in the temperature of said outer 50 atmosphere, thus to control the volume of condensate in the radiator and the volume of heating medium admitted thereto.
